UNITED STATES PATENT OFFICE.

JOHN B. LARKIN, OF PITTSBURG, PENNSYLVANIA.

ELECTRIC RAILWAY.

SPECIFICATION forming part of Letters Patent No. 650,586, dated May 29, 1900.

Application filed December 28, 1899. Serial No. 741,827. (No model.)

To all whom it may concern:

Be it known that I, JOHN B. LARKIN, a citizen of the United States of America, residing at Pittsburg, in the county of Allegheny and State of Pennsylvania, have invented certain new and useful Improvements in Electric Railways, of which the following is a specification, reference being had therein to the accompanying drawings.

10 My invention relates to certain new and useful improvements in railways, and is particularly adapted for use in connection with electric railways.

One object of my invention is to construct 15 a conduit used in connection with electric railways and which is particularly adapted to protect the conductor carrying the motive power.

20 A further object of my invention is to construct a conduit to be used in connection with electric railways and provide the said conduit with a transversely-operating slot-closer so arranged and supported as to prevent serious jolts and jars incident to the arrangement 25 of a slot-closer operated above the surface line of the street, owing to the fact that my improved slot-closer used in connection with the conduit is operated upon almost the same plane as the surface line of the street, 30 as well as below the same. By this construction the objections heretofore existing regarding slot-closers interfering with the constant crossing and recrossing traffic and which operate above the surface line of the 35 street are readily overcome.

35 A further object of my invention is to simplify the construction of conduit set forth in my copending application filed September 9, 1899, Serial No. 729,942, and November 3, 40 1899, Serial No. 735,684.

45 A further object of my invention is to provide a conduit with means to permit of the arrangement therein of a suitable feed-wire for the conductor, dispensing thereby with overhead wire connections for this purpose or intermediate line-stations.

50 A further object of my invention is to construct a conduit for electric railways with ample space for the conductor, feed-wire, supports therefor, and greater width of slot to permit of the operation of the trolley, and which will also permit of the easy access

thereto for adjustment or replacement of any of the parts used in connection therewith.

55 A further object of my invention lies in my improved operating means, suspended from the car, for operating the slot-closer to permit of the passage of the trolley through the conduit.

With the above and other objects in view 60 my invention finally consists in the novel combination and arrangement of parts, to be hereinafter more fully described, and specifically pointed out in the claims.

65 In describing the invention in detail reference is had to the accompanying drawings, forming a part of this specification, and wherein like numerals of reference indicate corresponding parts throughout the several views, in which—

70 Figure 1 is a side view of a car, partly broken away, showing my improved means for operating the slot-closer in full and dotted lines, the trolley being suitably connected to the operating means for the slot-closer, as 75 well as to the underneath face of the car. Fig. 2 is a cross-sectional view thereof and of my improved conduit. Fig. 3 is a cross-sectional view of my improved conduit, showing the slot-closer in an operative position. Fig. 80 4 is a top plan view thereof, one of the sections of the slot-closer broken away. Fig. 5 is a perspective view of one of the sections forming one of the side walls and a portion of the top of my improved conduit. Fig. 6 is 85 a perspective view of a pair of sections used in the construction of the slot-closer, each of these sections being broken away. Fig. 7 is a perspective view of one of the removable supporting and bracing stanchions used in 90 the conduit. Fig. 8 is a perspective view of the operating-arm for the slot-closer. Fig. 9 is an inverted plan view thereof.

95 Referring to the drawings by reference-numerals, 1 indicates a car; 2, the platform thereof, carrying on its underneath face a pulley-wheel 3, supported in the keepers 4. The platform 2 is further provided at the front of the pulley-wheel 3 with a vertical opening 5. The dashboard 6 of the platform 100 2 has suitably secured to the inner face thereof of a hook 7 to receive the end of the cord or cable 8 and support the same. This cord or cable engages the pulley-wheel 3 and extends

upwardly through the opening 5, as shown, and it also passes over the pulley-wheel 9, secured to the underneath face of the bottom of the car by means of the keepers 10 through 5 the eye 11', connected to the side of the operating-arm 12.

11 indicates a pair of apertured lugs formed integral with the arm 12, in which is mounted the pin 12'.

10 The operating-arm 12 is constructed of any suitable material and tapers in a curvilinear manner toward its lower end, as at 13, and has formed integral with its lower end a triangular-shaped stop-block 14, having a triangular-shaped working block 15, formed integral with the lower face thereof and which is of a smaller size. The operating-arm 12 is further provided with a pair of vertically-extending apertured lugs 16 to permit of pivotally connecting the arm 12 to the hanger 17, secured to the cross-piece 18, carried by the bottom of the car.

19 indicates a downwardly-extending spring connected to the hanger 17 and having its lower portion bearing against the front of the arm 12 and pin 12' for retaining the arm normally in an operative position.

Secured to the cross-piece 18 is a hanger 20, to which the upper end of the trolley 21 is 30 pivotally connected. The trolley is also connected to the rope or cable 8, as at 24, and provided at its lower end with a harp 22, in which is journaled a trolley-wheel 23.

25 indicates a stop arranged on the cable 8 between the operating-arm and trolley to raise the arm when the trolley is elevated by means of the cable. This stop also prevents the trolley from contacting with the operating-arm.

40 26 indicates the rails of the track, and 27 the track-bed, within which is arranged my improved conduit supported upon the cross-ties 28, which also support the track-bed and rails.

45 My improved conduit consists of a pair of inverted-L-shaped sections 29 30, forming the top and sides thereof, each having a transversely-extending flange 31 formed integral with the lower end of the outer face thereof, and this flange receives suitable fastening means 32 for securing the sections in position to the cross-ties 28. Each of these sections 29 30 is so arranged in relation to the other that they form an elongated slot between the 55 top inner edges of each of the sections when the same are set up.

33 indicates a series of transversely-extending supporting-studs formed integral with the top inner edges of each section, which are arranged a suitable distance apart. Each series of these studs is arranged opposite the series of the other section. The top inner edges of the sections are also provided with a concave cut-away portion 34 to receive the hinged end 60 of the slot-closer sections to be hereinafter described. The inner faces of the sides of each section of the conduit have suitably se-

cured thereto retaining-blocks 35, provided on one of their faces with a dovetailed wedge-shaped groove 36 to receive a wedge-shaped end 37 of the supporting and bracing stanchions 38 for securing the same in position. The blocks 35 are so arranged that when supporting the stanchions the lower edge of the same will be above the bottom 75 of the conduit, as will be seen at 39. The stanchions 38 are each provided with a pair of circular openings 40, through which pass feed-wires, (not shown,) and one of these openings is arranged at each side of the cut-away portion 41, formed centrally of the stanchions, as shown, having its bottom 42 adapted to have mounted thereon, in any desirable manner, a support 43, carrying an insulator 44 for the conductor 45.

My improved slot-closer consists of two separate series of rectangular plates or sections 46 47, of any desirable material, each series arranged opposite the other in a parallel manner. The two series of plates 46 47 are supported by the top of the conduit and upon the stanchions, and each series is adapted to operate transversely in an opposite direction. The sections 46 47 are provided with an elongated recess 48, opening 90 outwardly to allow of the mounting of the sections upon the top of the conduit, permitting the same to be supported upon the top of the stanchions, and also to allow of the sections being operated in a transverse 100 manner. Arranged in the recess 48 is a series of compression-springs 49. One end of each is mounted upon one of the studs 33, and the opposite end abuts against the inner side of the recess 41. The inner wall of one corner 105 of the recess 48 is cut away, as at 50, to permit of hingedly connecting thereto a slotted lug 51, formed integral with the adjacent corner of the opposite section. The top outer corner of each of the sections 47 46 is 110 rounded off, as seen at 52, so as to permit of the easy riding over the same of any vehicle.

The operation of my improved slot-closer is as follows: The car being propelled carries the operating-arm and trolley therewith. The 115 working block 15 (the downward movement of this block being limited by the stop-block 14) will force each series of plates or sections of the slot-closer apart in a transverse manner and permit of the movement of the trolley through the slot in the conduit. This transverse movement of the sections of the slot-closer caused by the passage of the working block 15 compresses the springs 49, which will expand and bring each pair of oppositely-arranged sections 46 47 together when the working block has passed from engagement between the same.

By providing the sections of the conduit with removable stanchions the same can be 130 easily replaced, if desired. The openings in the stanchions will permit of the satisfactory arrangement of feed-wires for the conductor and, as heretofore stated, overcome the ob-

jections as to intermediate line-stations and overhead wires, owing to the fact that the feed-wires can be easily arranged and supported within the conduit by means of the 5 openings formed in the stanchions, and, furthermore, these stanchions form a supporting means for the conductor and the sections of the slot-closer when in an open and closed position.

10 It is thought that the many advantages of my improved construction can be readily understood from the foregoing description, taken in connection with the accompanying drawings, and it will be noted that various changes 15 may be made in the details of construction without departing from the general spirit of my invention.

Having thus fully described my invention, what I claim as new, and desire to secure by 20 Letters Patent, is—

1. In an electric railway, a pair of suitably-arranged inverted - L - shaped sections for forming a conduit with an elongated slot arranged between the same, a series of supporting and bracing stanchions in the said conduit, two series of spring-actuated hingedly-connected sections mounted upon the top of 25 said L-shaped sections and stanchions forming a slot-closer, in combination with means 30 suitably suspended from a car for operating each series of sections of the slot-closer in a transverse manner, substantially as set forth.

2. The combination with a conduit provided with an elongated slot, of two series of 35 hingedly-connected sections mounted upon said conduit for closing said slot and engaging both faces of the top of the conduit, and means carried by a car for operating each series of sections in an opposite direction.

40 3. The combination with a conduit provided with an elongated slot, of two series of hingedly-connected sections mounted upon said conduit for closing said slot and engaging both faces of the top of the conduit, and means carried by a car for operating transversely each series of sections in an opposite 45 direction, substantially as described.

4. The combination with a conduit provided with an elongated slot, of two series of 50 hingedly-connected sections mounted upon said conduit for closing said slot and engaging both faces of the top of the conduit, and means carried by a car for operating transversely each series of sections in an opposite 55 direction and upon the same plane, substantially as described.

5. In an electric railway, the combination with a conduit provided with an elongated slot, of two series of hingedly-connected sections mounted upon said conduit for closing said slot and engaging both faces of the top of the conduit, and an operating-arm adapted to be suspended from a car and provided with a working block adapted to engage each series 60 of sections and operate the same in an opposite direction, substantially as described.

6. In an electric railway, the combination

with a conduit provided with an elongated slot, of two series of hingedly-connected sections mounted upon said conduit and closing 70 said slot and engaging both faces of the top of the conduit, and an operating-arm adapted to be suspended from a car and provided with a working block adapted to engage each series of sections and operate transversely the 75 same in an opposite direction, substantially as described.

7. In an electric railway, the combination with a conduit provided with an elongated slot, of two series of hingedly-connected sections mounted upon said conduit and closing 80 said slot and engaging both faces of the top of the conduit, and an operating-arm adapted to be suspended from a car and provided with a working block adapted to engage each series of sections and operate transversely the 85 same in an opposite direction and upon the same plane, substantially as described.

8. In an electric railway, the combination with a conduit provided with an elongated slot, 90 of two series of hingedly-connected spring-actuated sections mounted upon said conduit for closing said slot and engaging both faces of the top of the conduit, and means adapted to be carried by a car for operating each series of sections in an opposite direction, 95 substantially as described.

9. In an electric railway, the combination with a conduit provided with an elongated slot, 100 of two series of hingedly-connected spring-actuated sections mounted upon said conduit for closing said slot and engaging both faces of the top of the conduit, and means adapted to be carried by a car for operating transversely each series of sections in an opposite 105 direction, substantially as described.

10. In an electric railway, the combination with a conduit provided with an elongated slot, 110 of two series of hingedly-connected spring-actuated sections mounted upon said conduit for closing said slot and engaging both faces of the top of the conduit, and means adapted to be carried by a car for operating transversely each series of sections in an opposite 115 direction and upon the same plane, substantially as described.

11. In an electric railway, the combination with a conduit provided with an elongated slot, 120 of two series of hingedly-connected spring-actuated sections mounted upon said conduit for closing said slot and engaging both faces of the top of the conduit, and an operating-arm suitably suspended from a car and carrying a working block adapted to engage each series of said sections and operate the same 125 in an opposite direction, substantially as described.

12. In an electric railway, the combination with a conduit provided with an elongated slot, 130 of two series of hingedly-connected spring-actuated sections mounted upon said conduit, for closing said slot and engaging both faces of the top of the conduit, and an operating-arm suitably suspended from a car and car-

rying a working block adapted to engage each series of said sections and operate transversely the same in an opposite direction, substantially as set forth.

- 5 13. In an electric railway, the combination with a conduit provided with an elongated slot, of two series of hingedly-connected spring-actuated sections mounted upon said conduit for closing said slot and engaging both faces 10 of the top of the conduit, and an operating-arm suitably suspended from a car and carrying a working block adapted to engage each series of said sections and operate transversely the same in an opposite direction and 15 upon the same plane, substantially as described.

14. In an electric railway, the combination with a conduit provided with an elongated slot, and a spring-actuated slot-closer formed 20 of two series of sections, of a spring-actuated operating-arm suspended from a car and adapted to operate each series of sections in an opposite direction and upon the same plane, substantially as set forth.

- 25 15. In an electric railway, the combination with a conduit provided with an elongated slot and a spring-actuated slot-closer formed of two series of sections, of a spring-actuated operating-arm suspended from a car and 30 adapted to operate transversely each series of sections in an opposite direction and upon the same plane, substantially as set forth.

16. In an electric railway, the combination with a conduit provided with an elongated 35 slot and a spring-actuated slot-closer formed of two series of sections, of a spring-actuated operating-arm suspended from a car, and a working block carried by said arm adapted to operate each series of sections in an opposite 40 direction and upon the same plane, substantially as set forth.

17. In an electric railway, the combination with a conduit provided with an elongated slot and a spring-actuated slot-closer formed 45 of two series of sections, of a spring-actuated operating-arm suspended from a car, and a working block carried by said arm adapted to operate transversely each series of sections in an opposite direction and upon the same 50 plane, substantially as described.

18. In an electric railway, the combination with a conduit provided with an elongated slot and a spring-actuated slot-closer formed 55 of two series of sections, of a spring-actuated operating-arm suspended from a car, a stop-block formed integral with the lower end of said arm, and a working block formed integral with said stop-block and adapted to operate each series of sections in an opposite 60 direction and upon the same plane, substantially as described.

19. In an electric railway, the combination with a conduit provided with an elongated slot and a spring-actuated slot-closer formed 65 of two series of sections, of a spring-actuated operating-arm suspended from a car, a stop-block formed integral with the lower end of

said arm, and a working block formed integral with said stop-block and adapted to transversely operate each series of sections 70 in an opposite direction and upon the same plane, substantially as set forth.

20. In an electric railway, the combination of a conduit provided with an elongated slot, a series of removable supporting and bracing 75 stanchions arranged therein, an electrical conductor suitably supported by said stanchions, a spring-actuated slot-closer supported by said conduit and said stanchions, and means carried by a car and adapted to operate the said slot-closer in a transverse manner, substantially as described.

21. In an electric railway, the combination of a conduit provided with an elongated slot, a series of removable supporting and bracing 85 stanchions arranged therein, an electrical conductor suitably supported by said stanchions, a spring-actuated slot-closer supported by said conduit and said stanchions, an operating-arm carried by a car, and a working 90 block connected to said arm and adapted to engage and operate said slot-closer in a transverse manner.

22. In an electric railway, the combination of a conduit provided with an elongated slot, 95 a series of removable supporting and bracing stanchions arranged therein, an electrical conductor suitably supported by said stanchions, a spring-actuated slot-closer supported by said conduit and said stanchions, an operating-arm carried by a car, a stop-block 100 connected to said arm, and a working block formed integral with said stop-block and adapted to engage and operate said slot-closer in a transverse manner, substantially as de- 105 scribed.

23. In an electric railway, the combination of a conduit provided with an elongated slot, a series of removable supporting and bracing 110 stanchions arranged in said conduit and provided with a pair of openings for the passage of the feed-wire, an electrical conductor supported by said stanchions, two series of spring-actuated hingedly-connected sections forming the slot-closer mounted upon said conduit, and said stanchions, and means carried 115 by a car adapted to transversely operate each series of sections in an opposite direction, substantially as described.

24. In an electric railway, the combination 120 of a conduit provided with an elongated slot, a series of removable supporting and bracing stanchions arranged in said conduit and provided with a pair of openings for the passage 125 of the feed-wire, an electrical conductor supported by said stanchions, two series of spring-actuated hingedly-connected sections forming the slot-closer mounted upon said conduit, and said stanchions, a trolley suitably connected to a car and adapted to come into contact with said electrical conductor, and means connected to said trolley adapted to transversely operate each series of sections in an opposite direction to permit of the operation 130

of the said trolley within said conduit, substantially as described.

25. In an electric railway, the combination of a conduit provided with an elongated slot, a series of removable supporting and bracing stanchions arranged therein and provided with a pair of openings to permit of the passage of feed-wires, an electrical conductor suitably supported by said stanchions, two series of hingedly-connected spring-actuated sections forming the slot-closer supported upon said conduit and said stanchions, a trolley suitably suspended from the car and adapted to engage said conductor, an operating-arm suitably suspended from the car and connected to said trolley, and means carried by said operating-arm adapted to engage and operate transversely each series of sections in an opposite direction to permit of the operation of the said trolley in said conduit, substantially as set forth.

26. In an electric railway, the combination with a conduit provided with an elongated slot, a spring-actuated slot-closer carried by said conduit, means arranged in said conduit for supporting said slot-closer as well as bracing the conduit, and an electrical conductor suitably mounted upon said means.

27. The combination with a conduit, of means for suitably bracing the same, and a spring-actuated slot-closer carried by said conduit and supported by said means.

28. The combination with a conduit, of a slot-closer suitably mounted thereon and engaging both faces of the top thereof, and means arranged in said conduit for supporting said slot-closer.

29. The combination with a conduit, of a transversely-operating slot-closer suitably mounted in the top engaging both faces thereof, an electrical conductor, and means arranged in said conduit for supporting said slot-closer and conductor.

30. In an electric railway, a conduit provided with a suitable slot, a transversely-operating closer suitably connected to the top of said conduit and engaging both faces thereof, an electrical conductor, means arranged in said conduit for supporting said slot-closer and conduit, in combination with means carried by a car for operating said slot-closer, as and for the purpose set forth.

31. In an electric railway, a conduit provided with a suitable slot, a transversely-operating slot-closer suitably connected to the top of said conduit, an electrical conductor, means arranged in said conduit for supporting said slot-closer and conduit, in combination with a trolley supported from a car and adapted to engage said conductor, and an operating-arm carried by a car and adapted to operate said slot-closer to permit the passage of said trolley through said slot, substantially as described.

32. In an electric railway, the combination with a conduit provided with a suitably-supported transversely-operated slot-closer, of

an operating-arm suitably suspended from a car, a stop-block formed integral therewith, and a working block connected to said stop-block and adapted to operate said slot-closer, as and for the purpose described.

33. The combination with a conduit, of a transversely-operating slot-closer formed of a series of sections suitably mounted on the top of said conduit and engaging both faces thereof, an electrical conductor, and means arranged in said conduit for supporting said conductor and slot-closer, substantially as set forth.

34. The combination with a conduit, of a transversely-operating spring-actuated slot-closer formed of a series of sections suitably mounted on the top of said conduit and engaging both faces thereof, an electrical conductor, and means arranged in said conduit for supporting said slot-closer and conductor, substantially as described.

35. The combination with a conduit, of a transversely-operating spring-actuated slot-closer mounted upon the top of said conduit, an electrical conductor, a series of retaining-blocks arranged in the said conduit, and means connected to the said blocks and adapted to brace the said conduit and support said slot-closer and conductor, substantially as described.

36. In an electrical railway, a conduit constructed of a series of sections so arranged as to form an elongated slot, a series of studs or pins suitably arranged upon the said sections, a spring mounted upon each of said studs or pins, a slot-closer formed of a series of sections mounted upon the said conduit so as to engage the upper and lower faces thereof and be operated by said springs to close said slot, and a spring-actuated operating-arm suspended from a car and adapted to operate said slot-closer to open the slot, substantially as described.

37. In an electrical railway, a conduit constructed of a series of sections so arranged as to form an elongated slot, a series of studs or pins suitably arranged upon the said sections, a spring mounted upon each of said studs or pins, a slot-closer formed of a series of sections mounted upon said conduit so as to engage the upper and lower faces thereof and be operated by said springs to close said slot, a spring-actuated operating-arm carried by a car, and a working block carried by said arm and adapted to operate said slot-closer to open said slot, substantially as described.

38. In an electrical railway, a conduit constructed of a series of sections so arranged as to form an elongated slot, a series of studs or pins arranged upon the said sections, a spring mounted upon each of said studs or pins, a slot-closer formed of a series of sections mounted upon the said conduit so as to engage the upper and lower faces thereof and be operated by the said springs to close said slot, a series of stanchions arranged in the said conduit and adapted to support said slot-

closer, and a spring-actuated operating-arm suspended from a car and adapted to operate said slot-closer, substantially as described.

39. In an electrical railway, a conduit constructed of a series of sections so arranged as to form an elongated slot, a series of studs or pins arranged upon the said sections, a spring mounted upon each of said studs or pins, a slot-closer formed of a series of sections mounted upon the said conduit so as to engage the upper and lower faces thereof, and be operated by the said springs to close said slot, a series of stanchions arranged in said conduit and adapted to support said slot-closer, 15 a spring-actuated operating-arm carried by a car, and a working block carried by said arm and adapted to operate said slot-closer to open said slot, substantially as described.

40. In an electrical railway, a conduit constructed of a series of sections so arranged as to form an elongated slot, a series of studs or pins arranged upon the said sections, a spring mounted upon each of said studs or pins, a slot-closer formed of a series of sections 25 mounted upon said conduit so as to engage the upper and lower faces thereof and be operated by the said springs to close said slot, a series of stanchions arranged in said conduit and adapted to support said slot-closer, 30 means arranged in said conduit for supporting said standards, a spring-actuated operating-arm carried by a car, and a working block carried by said arm and adapted to operate said slot-closer to open said slot, substantially as described.

41. The conduit for an underground railway constructed of side walls having top portions extending at right angles thereto, and the slot-closer mounted and operating upon 40 the upper and lower faces of the angular portions.

42. The conduit for an underground railway constructed of side walls having top portions extending at right angles thereto, the slot-closer mounted and operating upon the upper and lower faces of said angular portions, and the springs mounted within the said slot-closer and adapted to keep the same normally in a closed position.

43. The conduit for an underground railway constructed of side walls having top portions extending at right angles thereto, the slot-closer mounted and operating upon the upper and lower faces of said angular portions, the springs mounted within the said slot-closer and adapted to keep the same normally in a closed position, and the stanchions arranged in the conduit for bracing the same and supporting said slot-closer.

44. The conduit for an underground railway constructed of side walls having top portions extending at right angles thereto, the slot-closer mounted and operating upon the upper and lower faces of said angular portions, the springs mounted within the said slot-closer and adapted to keep the same normally in a closed position, the series of re-

taining-blocks connected to the inner face of the side walls of the conduit, and the series of stanchions secured in the retaining-blocks 70 and adapted to brace the conduit and support the slot-closer.

45. In an underground railway, a conduit provided with an elongated slot, a spring-actuated slot-closer formed of two series of 75 sections mounted upon said conduit and operating within the said slot, and means carried by a car for operating said slot-closer.

46. In an underground railway, a conduit provided with an elongated slot, a spring-actuated slot-closer mounted upon said conduit and operating within the said slot, a series of stanchions arranged in said conduit 80 and adapted to support said slot-closer, and means carried by a car for operating said slot-closer.

47. In an underground railway, a conduit provided with an elongated slot, a spring-actuated slot-closer mounted upon said conduit and operating within said slot, a series of retaining-blocks secured within said conduit, a series of supporting-stanchions connected to the said blocks and adapted to brace said conduit and support said slot-closer, and means carried by a car for operating said slot-closer. 95

48. A conduit for underground railways provided with an elongated slot, and a spring-actuated slot-closer operating within the said slot and upon the upper and lower faces of said conduit.

49. In an electrical railway, a conduit provided with an elongated slot, a spring-actuated slot-closer operating within the said slot and upon the upper and lower faces of said conduit, and means supported from a car 105 adapted to operate said slot-closer.

50. A conduit for underground railways provided with an elongated slot, a spring-actuated slot-closer mounted and operating within said slot and upon the upper and lower faces 110 of said conduit, and a series of stanchions arranged in said conduit and adapted to support said slot-closer.

51. In an electric railway, a conduit provided with an elongated slot, a spring-actuated slot-closer operating within the said slot and upon the upper and lower faces of said conduit, a series of supporting - stanchions arranged in the said conduit and adapted to support said slot-closer, and means suspended 115 from a car for operating the said slot-closer.

52. A conduit for underground railways provided with an elongated slot, a slot-closer operating within the said slot and upon the upper and lower faces of said conduit, springs 125 arranged in the said slot-closer for normally keeping the same within said slot, and a series of stanchions arranged in the said conduit and adapted to support said slot-closer.

53. In an electric railway, a conduit formed 130 with a slot, a slot-closer operating within the said slot and upon the upper and lower faces of said conduit, springs arranged in the said slot - closer for normally keeping the same

within the said slot, a series of stanchions arranged in the said conduit and adapted to support said slot-closer, and means suspended from a car for operating the said slot-closer.

5 54. A conduit for underground railways provided with an elongated slot, a slot-closer operating within the said slot and upon the upper and lower faces of said conduit, springs arranged in the said slot-closer for normally keeping the same within said slot, an electrical conductor, and a series of stanchions arranged in the said conduit and adapted to support said conductor and slot-closer.

10 55. In an electric railway, a conduit provided with a slot, a slot-closer operating within

the said slot and upon the upper and lower faces of said conduit, springs arranged in said slot - closer for normally keeping the same within said slot, an electrical conductor, a series of stanchions arranged in the said conduit and adapted to support said conductor and slot-closer, and means suspended from a car for operating said slot-closer. 20

In testimony whereof I affix my signature in the presence of two witnesses.

JOHN B. LARKIN.

Witnesses:
